UNITED STATES PATENT OFFICE

2,589,740

CONTAINER SEALING MACHINE

Henry B. Silver, Brooklyn, N. Y., assignor to
 Plastic Seal Corporation, Brooklyn, N. Y., a
 corporation of New York

Application April 27, 1950, Serial No. 158,365

23 Claims. (Cl. 226—80)

1

The present invention relates to a machine for sealing bottles and other containers, and more particularly to the type by which a ribbon of viscous sealing material is discharged from a nozzle about the joint between the cap or other enclosure and the body or neck of the container.

An object of this invention is to provide a novel and improved sealing machine of the type mentioned, which is fully automatic and high speed in operation.

Another object hereof is to provide a sealing machine of novel and improved construction, of the class described, wherein the discharge nozzle revolves about the bottle or container to be sealed.

A further object hereof is to provide a novel and improved machine of the kind set forth, wherein the discharge nozzle is in constant rotation about sealing position and yet will discharge sealing material only when a bottle or container is at sealing position.

Another object hereof is to provide a sealing machine of the nature mentioned, wherein nozzle discharge pressure is automatically controlled to insure uniform nozzle performance.

A further object of this invention is to provide a novel and improved sealing machine as set forth, which employs a constantly revolving discharge nozzle associated with means to automatically shift the nozzle out of the path of bottles or containers already sealed or to be sealed.

Still another object hereof is to provide a machine of the character set forth, of novel and improved construction, wherein the ribbon ends of the seal effected, overlap each other to insure that the joint protected is impervious to air and moisture.

Another object hereof is to provide a sealing machine of novel and improved construction of the class described, which is adjustable for use for bottles and similar containers of different sizes.

A further object hereof is to provide a novel and improved sealing machine of the type described, which properly positions and holds the container to be sealed at sealing position, and releases such hold in proper time during the cycle of machine operation, and further, insures that such release takes place.

Another object of this invention is to provide a novel and improved sealing machine of the kind described, which permits easy removal and replacements of various parts subject to wear, and requires a dismantling of a minimum number of parts to accomplish this.

2

Still a further object hereof is to provide a sealing machine of novel and improved construction, of the class set forth, affording various safety means to insure positive operation of certain included mechanisms in order to avoid damage to the machine which might otherwise occur if for some reason or other, such mechanisms fail to operate in the organized scheme of operation.

10 A further object hereof is to provide a novel and improved, fully automatic, high speed sealing machine of the type mentioned, which is efficient in carrying out the purposes for which it is designed.

15 Other objects and advantages will become apparent as this disclosure proceeds.

In the accompanying drawings forming part of this specification, similar characters of reference indicate corresponding parts in all the views.

20 Fig. 1 is a front view of a sealing machine embodying the teachings of this invention. In this preferred embodiment, the main shaft is vertical and among other things, carries a cam gear and a nozzle gear, so named for convenience. The nozzle gear shown, is the lower one. Between the said gears, the main shaft passes through a main plate which is part of the framework.

25 Fig. 2 is a perspective view showing the principal framework of the machine with some associated components of a conveyor system for transporting one bottle at a time to sealing position and away therefrom.

30 Fig. 3 is a central section through the main shaft, the gears it carries and shown also are various associated components.

35 Fig. 4 is a magnified sectional view of the upper part of the shaft shown in Fig. 3, showing in particular a section through the packing box employed in the system for supplying viscous sealing material through the main shaft which affords a passageway to the nozzle.

40 Fig. 5 is a perspective view showing the two parts of the casing which constitutes the packing box.

45 Fig. 6 is a longitudinal section through a removable sleeve included in the assembly shown in Fig. 4.

50 Fig. 7 is an auxiliary cam to insure operation of a container-centering member movement to clear the closure of the container to be sealed so that such closure is properly exposed to nozzle action.

55 Fig. 8 is a section through the nozzle-carrying bracket which is swingably mounted on the underside of the nozzle gear. Such bracket also

includes the nozzle valve, which is here also shown in section.

Fig. 9 is an end view of Fig. 8. Here can be seen the rack and gear employed to swing the nozzle-carrying bracket to and away from sealing discharge position relative the bottle to be operated on.

Fig. 10 shows the two halves of the nozzle proper. This view is in perspective.

Fig. 11 is a perspective view of a shim or gasket interposed between such nozzle halves on assembly.

Fig. 12 is a partly sectional view showing associated cam and follower means used to control the opening of the nozzle valve of Fig. 8.

Fig. 13 is a partly sectional view showing associated cam and follower means used to control the closing of the said nozzle valve.

Fig. 14 shows in perspective the mechanism illustrated in Figs. 12 and 13 in operative relation with the nozzle valve, and also includes means which permits the opening of such valve only when a bottle is in sealing position.

Fig. 15 is a diagrammatic view of the system employed to feed viscous sealing material from a hopper to the main shaft from whence it gets to the nozzle. Also here included is a means to control the pressure of such supply flow.

Fig. 16 is a perspective view of such pressure control means.

Fig. 17 is a section taken at lines 17-17 in Fig. 16.

Fig. 18 is a section taken at lines 18-18 in Fig. 16.

Fig. 19 shows means used to open and close valve mechanism included in the pressure control means illustrated in Fig. 16.

Fig. 20 is a top view of Fig. 19.

Fig. 21 is a perspective view of one of the parts included in the assembly shown in Fig. 19.

Fig. 22 is an enlarged perspective view of the rack and gear set shown in Fig. 9, as well as of the bracket slidably supporting said rack. Also included is an indexing means for holding the nozzle in its extreme position. It might here be noted that movement of said rack is controlled by a special cam means, the cooperating follower of which is here shown carried on the rack.

Fig. 23 shows the rack bracket included in Fig. 22. Such bracket is shown mounted on the underside of the nozzle gear. This gear has a suitable opening for the rack to slide therethrough.

Fig. 24 shows the spring-loaded engagement member which cooperates with the index disc for holding the position of the nozzle-carrying bracket.

Fig. 25 shows the front view of a one piece cam structure used to make the special cam means for controlling the rack movement.

Fig. 26 is a plan view of Fig. 25.

Fig. 27 is a side view of Fig. 26.

Fig. 28 is a development of the surface of this cam structure, and in this view is indicated the manner of cutting same into several parts which shall serve as the special cam means for controlling the rack movement.

Fig. 29 is a perspective view of the rack-controlling cam means which was made of the original one piece structure illustrated in Fig. 25. Such cam means comprises two movable elements which are relatively small, and positioned above a main cam part. Said two small cam parts are mounted for independent, vertical

movement towards and away from the main lower part. The movement of said two small upper cam parts are controlled by cam tracks on the underside of the cam gear.

Fig. 30 is a perspective view of a cam follower assembly associated with one of the movable cam parts included in Fig. 29; the cam follower associated with the other movable cam part being shown in Fig. 29.

Fig. 31 is a side view of a component shown in Fig. 30, serving as an auxiliary cam to insure lifting of the cam part controlled by the means otherwise shown in Fig. 30.

Figs. 32 and 33 are development views of the cam means of Fig. 29, shown in different conditions during operation. These views will aid in explaining the operation of said cam means.

Fig. 34 is a top plan view of the main plate included in the framework of this machine, showing preferred locations of the apparatus mounted thereon. This layout is different from that shown in Fig. 1, where the respective positions of the parts have been chosen to attain better clarity in illustration so that pertinent parts appear separate instead of behind one another.

In the preferred embodiment of this invention shown in the drawings and particularly referring to Figs. 1 and 2, a table 50 is part of the machine's framework which includes the stationary vertical posts 51 carrying fixed at their top ends, the plate member 52. These posts arranged one at each side in front and one in the rear of the machine, carry a slidably mounted carriage structure whose position along such posts is adjustable by manipulation of a handwheel 53 journaled atop the plate member 52, and in threaded engagement with the upwardly positioned screw 54 extending from the top member 55 of the carriage structure. The bottom member of said carriage is a horizontally positioned plate member 56 mounted on all the posts 51. Said member 56 will hereinafter be called the main plate. It is connected to the upper member 55 by the three rods 45, on two of which is fixed a bridge piece 58 intermediate said top and bottom carriage members.

A vertically positioned round tubular member 59, having an outward flange 59' intermediate its ends, is fixedly mounted on the main plate 56 as shown in Fig. 3, and extends through the circular hole 60 in said plate. Suitably seated bearings 61 and 62, at top and bottom of the member 59 and housed therein, serve the main shaft denoted generally by the numeral 63, which extends through said member 59. A gear 64, hereinafter called the nozzle gear, is keyed by 65 at the bottom end of the main shaft 63. This gear is spaced from and below the main plate 56. Above said main plate, a gear 66 is revolvably mounted about the tubular member 59. This gear 66 is hereinafter designated as the cam gear. The members denoted respectively by the numerals 67, 68 and 69 are threadedly engaged lock rings, while ring 70 is of suitable material to act as bearing surface for the face of the hub of the cam gear 66. The ring 67 is threadedly engaged on the top end of the main shaft 63 and otherwise, suitably keyed thereto by other releasable means not shown; such ring serving to hold the main shaft mounted. The nozzle gear 64 and the cam gear 66 are driven from a main power shaft 71 which is mounted vertically and has a longitudinal slot 72 which permits sliding movement of the sleeve 73 suitably keyed

on such shaft 71 and journalled to the main plate 56. This sleeve carries a gear 74 which is in constant engagement with the cam gear 66, and also a gear 75 which is in constant engagement with the nozzle gear 64. It is evident that this gear-carrying sleeve 73 will move along with the carriage structure which includes the main plate 56. The gear ratios are such that the nozzle gear 64 shall turn two revolutions for each revolution of the cam gear 66.

The main shaft 63 has an axial bore therethrough for the slidable tube 76, which at its extending lower end, terminates in a bottle-centering cup 77. Within tube 76 is the slidable rod 78, adapted to be lowered to hold the centered bottle in true sealing position, while the centering cup is raised to permit the nozzle designated generally by the numeral 79 to do its work. The lower end of rod 78 is provided with a soft metal tip 80 so as not to mar the cap 81 which closes the mouth of the bottle 82 being operated on.

The upper portion 63' of the main shaft is of reduced diameter and at its junction with the remainder of such main shaft, has surrounding it, an annular space 83. Opening in the bottom end of the said main shaft 63 is a vertical bore 84 reaching only to the region of the annular space 83, and made communicative with said annular space by means of a duct 85. To drill this duct 85, it was made the continuation of the hole later tapped and plugged at 86.

Said upper portion 63' of the main shaft, has its own upper portion slightly reduced and exteriorly threaded, for engagement by the top end of a sleeve member denoted generally by the numeral 87 positioned about said upper portion 63' of the main shaft. Said sleeve member rotates with said shaft, and is capable of being unscrewed and removed from said shaft, whenever required to be replaced when worn in the packing box 88. It is best to provide said sleeve member with a flange 87' to attain a secure joint against leakage.

Further as shown in Fig. 4, said sleeve member 87, intermediate its ends, has the diametrically opposite holes 89 and 90 through its wall. Above these holes, the said sleeve and the main shaft portion 63' are in snug fit to avoid any leakage between them at their top ends. From above these holes 89 and 90, and all the way downward through the sleeve member, there is an annular space 91 between said sleeve and shaft portion, which space is a communicative extension of the annular well 83. It is evident that any sealing fluid in space 92 in the packing box 88, is free to flow through the holes 89 and 90 in the sleeve member 87, into the annular space 91, thence into the annular space or well 83, the duct 85, then downwardly in bore 84 in the main shaft 63, and then finally to the nozzle valve 93 controlling the flow to the discharge nozzle 79.

The preferred construction of the sleeve member 87 is shown in Fig. 6, where for the greatest part of its length it is of uniform outside diameter, but the thickness of wall below the holes 89 and 90 is less than above them, in order that the annular space 91 be formed when said sleeve is mounted on shaft portion 63'.

The packing box 88 is made of two identical halves 94 and 95, which when assembled form a casing having three annular races, one above the other, and respectively designated by the numerals 96, 92 and 97. The upper and lower races 96 and 97 hold packing 98 and 99. Each such

part 94 and 95, has a threaded hole 100 to receive ends of respective pipes 101 and 102, also the holes 103 to hold bolts to effect assembly, as well as the flange parts 94' and 95' so that the packing box can be mounted depending from the underside of the bridge piece 58, so that hole 104 therethrough can act as a well for oil, into which well the joined upper ends of the shaft portion 63' and its sleeve member 87 protrude. Said sleeve shown in Fig. 4, is in bearing contact with the inner semi-circular concave edges of the ribs or partitions 105 and 106. The dished member 107 acts as an oil reservoir under the packing box 88 onto which it is detachably mounted by means of the screws 108. The numeral 109 indicates a washer of packing material suitably cemented to lie in the central hole in said oil reservoir 107, through which hole the sleeve is in contact with said ring or washer 109. It is evident that to remove and replace the packing or the sleeve member, all that is necessary is to dismantle the packing box 88 which is a simple matter, and does not require the removal of the main shaft and in no manner molests or upsets the adjustment of the bottle centering mechanism.

Referring to Figs. 1, 3, 8 and 9, it is noted that on the underside of the nozzle gear 64 are carried two brackets 110 and 111, which serve for swingably mounting thereon the nozzle bracket 112 carrying a gear 113. Also, on the underside of said nozzle gear, near an opening therethrough denoted in Fig. 23 by the numeral 114, is mounted a bracket 115, on which is slidably supported a vertically movable rack member 116. This rack is in engagement with the gear 113, extends through the opening 114 aforesaid, and carries a roller 118 which acts as a cam follower controlled by a cam means shown in Figs. 1 and 29. This cam means which will be later described in detail, consists principally of the cam parts 119, 120 and 121 which cooperate in a special manner. Cam part 119 is fixed to the underside of the main plate 56. Cam parts 120 and 121 are positioned under said plate and are independently movable towards and away from, in vertical direction, in relation to the cam part 119, which is below them. Follower 122 is adapted to control the movement of cam part 120. A follower means 123 shown in Fig. 30, is used to control the movement of the cam part 121. Of course, separate cams cooperate with the follower devices 122 and 123, as will be set forth.

Extending from the upper face of the cam gear 66, are two concentric cam tracks denoted by the numerals 124 and 125 respectively. Extending from the underside of said cam gear, are four concentric cam tracks denoted by the numerals 126, 127, 128 and 129 respectively. All six mentioned cam tracks on the cam gear are ring mounds which are circular on the faces of the gear respectively, of varying heights from the face of the gear, as is well known in the machine art to raise and lower a co-operating follower so as to give the follower a predetermined movement, and to actuate the followers in a predetermined timed relation.

Follower means 130 cooperates with cam track 124, to raise and lower the tubular member 76 which carries the bottle-centering cup 77. The follower means 131 cooperates with cam track 125, to raise and lower the hold-down rod 78. The numerals 130' and 131' denote rollers at the lower ends respectively of the vertical, axially slidable rods 132 and 133, which are post-

tioned through bosses integral of the bridge-piece 58. These rods are pivotally pinned to, and in their movement are respectively adapted to give movement to the beams 134 and 135 which are pivotally mounted on said bridge piece. In turn, said beams are pivotally engaged in suitable manner to the members 76 and 78 respectively. The numerals 136 and 137 designate tension coil springs which hold the rollers 130' and 131' in constant contact with their associated tracks. Should spring 136 break accidentally while the machine is running, the nozzle 79 would hit against the centering cup 77, and considerable damage would occur. This is prevented with certainty because of the presence of an auxiliary means 139 mounted on the upper face of the cam gear 66, and the cam roller 138 carried on the rod 132, because said rod will be brought downward to raise the centering cup out of the locus of movement of the nozzle 79, when said roller 138 passes under the downwardly sloping cam face 139. (See Fig. 7.)

Follower means 140 shown in Figs. 1, 12 and 14, cooperates with cam track 128, to shift cam means 141 which is atop the nozzle gear 64, to open the nozzle valve 93. The follower means 142 shown in Figs. 1, 13 and 14, cooperates with the cam track 127, to shift cam means 143 which is atop the nozzle gear 64, to shut said nozzle valve.

Follower means 122 shown in Figs. 1 and 29, cooperates with cam track 129 to accomplish movement of the cam part 120. Follower means 123 shown in Fig. 30 and indicated in Fig. 1, cooperates with the cam track 126 for movement of the cam part 121. As mentioned, said cam parts in cooperation with the cam part 119, determine movement of rack 116 and hence of the swing of the nozzle 79 to and away from sealing position. As an auxiliary means to assure nozzle swing away from sealing position, in order to avoid damage to the machine if for any reason such cam part movement does not occur when required due to spring failure, there is the member 144 depending from the cam gear 66. Such member presents the upwardly sloping cam face 144' which when contacted by the auxiliary roller 145 on the follower means 123, will effect the raising of the cam part 121 (see Fig. 30).

Referring to Figs. 12, 13 and 14, it is to be noted that when the roller 146 of the follower means 140, is in lowered position as shown in Fig. 12, it will contact the vertical surface of the cam projection 141', and due to the rotation of the nozzle gear 64, the shaft 148 will turn a fraction of a revolution and cause arm 147 to contact and shift the slide rod 159 of the nozzle valve 93, to "open" position for sealing substance to enter the nozzle 79. When the roller 149 of the follower means 142 is in lowered position as shown in Fig. 13, it will contact the vertical surface of the cam projection 143' and due to the rotation of the nozzle gear 64, the shaft 150 will turn a fraction of a revolution and hence arm 151 will contact and shift the slide rod 159 back to "closed" position whereby the supply of sealing substance is cut off to the nozzle 79. Arms 157 and 158, connected by a tension coil spring 49, are fixedly carried on their respective shafts 148 and 150, and travel between adjustable stops (not shown) on the underside of the nozzle gear 64. As soon as the rollers 146 and 149 cease contact with the respective cams 141 and 143, the tensed spring 49 will return said cams to their original positions respectively. Adjustable bolts 156 and 155

are provided on the slide-shifting arms 147 and 151, to determine movement of the valve slide rod 159.

To accomplish that the nozzle valve 93 remain closed when and if there is no bottle in sealing position, the follower means 140 is of such construction that downward movement of the member 160 carrying the roller 146 is not permitted unless there is a bottle at sealing position. Therefore note the vertically positioned rotatable rod shaft 161 carrying the laterally extending bars 162 and 163. The said bar 162 terminates in a block 164 which is normally maintained positioned in contact and between the flange 161' and plate 56, which prevents downward movement of member 160, and the position of said block is so maintained by the stressed tension coil spring 166. The bar 163 is suitably shaped and dimensioned that when a bottle comes into sealing position, said bottle will have moved the bar 163 to turn the rod shaft 161 whereby block member 164 is shifted away as in Fig. 14, so that member 160 is free to be moved. In Fig. 14, the bar or arm 163 is behind the bottle, and contacting same. As soon as the bottle at sealing position moves away, the spring 166 will return the block member 164 for positioning itself between the flange 161' and the plate 56.

In Fig. 12, the vertically positioned tubular body member 167 is securely positioned through a suitable opening in the main plate 56, and has the outer flange 167', and also the internal tubular liner 168 in which is free to slide in piston-like manner, the lower portion of the member 160. The upper portion of this member 160 is bifurcated. The tines 161'' have longitudinal slots 170 to serve as tracks for a pin bolt 171 extending from each end of the fork 172 carrying the roller 173 which is maintained in constant contact with the cam track 128 on the cam gear 66, by means of the rather strong compression coil spring 174 in the hollow 175 of the member 160. In this hollow, piston-like, is the downward shank 176 of fork 172. The numeral 177 denotes a rather weak spring between flanges 167' and 161'.

While block 164 is in position holding part 160 from downward movement, any downward movement of shank 176 due to action of cam track 128, will only cause the spring 174 to be stressed, and of course maintain roller 173 in constant contact with said cam track. When block 164 is moved away to permit downward movement of part 160, any downward movement of the shank 176 due to action of the said cam track 128, will in turn cause downward movement of part 160 to lower the roller 146 into the path of cam 141; the stiffness of spring 174 being sufficient to allow this to occur. Spring 177 serves to shift part 160 upward upon upward movement of the shank 176, so that block member 164 may swing into position between the flanges 161' and 167'. So that roller 173 be in proper position with respect to the track 128, part 160 is maintained against axial rotation by means of the fixed pin 180 which is free in vertical groove 181 cut in the wall of the part 160.

In Fig. 13, the numeral 182 designates the shank of a holder 183 of the roller 184 which contacts the cam track 127 on the underside of the cam gear 66. This shank 182 extends downwardly through a suitable boss 185 on the main plate 56, and is slidably therethrough within the liner 186. This shank carrying roller 187 at its lower end, is maintained against axial rotation by means of the fixed pin 188 free in the vertical

groove 189 cut in the shank member 182. This is so that roller 184 shall remain in proper position with respect to the cam track 121. Said roller is constantly maintained in contact with said cam track by means of the compression coil spring 190 positioned as illustrated.

Now, referring to Figs. 8, 9, 10 and 11, the nozzle bracket designated generally by the numeral 112, may be a casting of such construction so as to have a nozzle 79 mounted onto its lower end, and so that its upper portion may serve as a shaft to be journaled in suitable brackets 110 and 111, and extend through one of such brackets, where as such shaft, it carries gear 113 and a disc member 191. Also, the body of said casting shall include intermediate said top and bottom portions thereof, a suitable structure to serve as the control valve 93. In the construction illustrated, the underside serving as a base for the nozzle is horizontal, the axis of the shaft portion 179' is horizontal and the control valve 93 has a horizontal slide rod, parallel with the axis of rotation of said shaft part. The brackets 110 and 111 are secured depending from the underside of the nozzle gear 64.

Said bracket casting is provided with a bore 192 which is communicative with the nozzle designated generally by the numeral 79, and with a horizontal bore in its middle part, through which latter extends the slide rod 159 of the control valve 93; both said bores being in communication when the slide rod 159 is shifted so that its reduced section 159' is at the intersection of both said bores in the nozzle bracket. In the condition shown in Fig. 8, the valve 93 is closed.

The upper portion of said bracket casting may be made of two parts 193 and 194, held together by bolts 195, and rotatably mounted on the tubular member 196 which is fixed through the supporting bracket 111, is communicative with the bore 192, and by piping 197 shown in Fig. 1, is connected to lower opening 84' of the bore 84 in the main shaft 63.

The nozzle 79 is made up of the parts shown in Fig. 10, and consists of the two halves 198 and 199, which are assembled with a shim 203 between them to make a leak-proof unit, affording the discharge orifice 201. The nozzle halves, in their meeting surfaces, present an L-shaped channel, which if without the shim in assembly, would be closed at discharge end of the nozzle. The cut-out 203 in the front edge of the shim, permits the nozzle discharge to be in proper ribbon form, and when the nozzle is at sealing position, such ribbon is discharged horizontally in a vertical plane. The passage in the nozzle, when the nozzle is assembled and mounted, is of course communicative with the lower opening of the bore 192. It is evident as shown in Fig. 9, that when the rack 116 moves downward, the nozzle 79 will be swung away from sealing position. When the rack moves upward, the nozzle will be swung into sealing position where the discharge opening 201 accomplishes ribbon discharge in a vertical plane. To permit some adjustment of nozzle position, the slots 204 may be provided. The contour of nozzle discharge face is preferably made to conform with that of the container region it sets adjacent to. Other incidents of nozzle design are described in prior art hereinafter mentioned. It is pertinent to note that in the present structure, the channel end elements 198' and 199', if worn or damaged, permit repair of the nozzle halves by merely grinding or otherwise surfacing

these nozzle halves true so that the shim alone determines nozzle opening.

Fig. 15 shows a system for sealing substance supply and for the control thereof. The numeral 205 denotes a rotary pump which forces sealing substance from the hopper 206 through a filter 207 to insure a uniform consistency. From the filter, such substance enters another rotary pump 208 which discharges through pipe 102 into the annular space 92 within the packing box 88, and from there such substance as can be seen in Fig. 4, passes through the holes 89 and 90, into space 91 and then into space 83, duct 85, down passage-way 84 in main shaft 63, thence through piping 197 into the nozzle bracket 112, down through the bore 192, and is there controlled by valve 93 for final discharge through the nozzle 79.

A pressure control means designated generally by the numeral 210, and to be described hereinafter, has two port openings, to which connections are made by the pipes 209 and 211, respectively. The pipe 209 is directly connected to pipe 101 which leads to the space 92 in the packing box 88. A pipe 213, having a hand-controlled valve 214 interposed therein, connects to pipe 211 and to the intake port of the second pump 208. Piping 215 affords a passage from the pipe 213 at a point between the valve and pipe 211, to the intake port of the first pump 205.

Gears 216 and 217 on the pump rotors, are in engagement and are driven by or from the horizontally positioned shaft 219 mounted atop the main plate 56 in suitable bearings 218. Said shaft 219 is driven from the main power shaft 71, by gearing not shown, which drives the bevel gear 220 carried on the said shaft 219.

The control means 210 may have a metal block body 221, for various valve mechanisms arranged in a special functional relationship as will be set forth. Referring to Figs. 16 through 21, the numeral 222 is a bore within said block body, in which is properly fitted a valve slide rod 223 having an intermediate reduced section. This rod extends out of said body where said rod terminates in a plate member 224 which is pivotally mounted to said rod by means of an axis pin 225. This plate has an elongated hole 226 therethrough intermediate two other holes 227 and 228. Said plate is loose on the shaft 219 which drives the pumps; said shaft being through the middle hole 226. The cams 229 and 230 are carried on the shaft 219, one at each side of the plate member 224. A roller 231 is carried on one side of the plate on a stud pin 232 fixed in hole 227. Another roller 233 is carried on the other side of said plate member 224, on a stud pin 234 fixed in the hole 228. The action of the cams when shaft 219 rotates, is to reciprocate the slide rod 223 a definite amount.

It is to be noted that the movement of said valve slide rod 223 is intermittent, and occurs only upon contact of one of the cams and its related roller. When said cams 229 and 230 are in congruent relation on the shaft 219, said slide rod 223 will be in "open" position during half of each revolution of said shaft, and in "closed" position during the other half. However, by altering the angular relation of the positions of said cams on shaft 219, the ratio of time in "open" position to the time in "closed" position aforementioned, may be changed. Also to be noted, is that the use of a non-rigid connection for associating the valve slide rod 223 to the shaft 219, avoids the ne-

cessity of an ever-precise assembly whereby the axis of said rod shall be perpendicular and intersecting the axis of said shaft. To attain precision in the movement of said slide rod 223, the plate 224 shall be in good slide fit on shaft 219, and the block member 221 shall be mounted on the frame of the machine, as for instance on the plate member 56, so that there is such intersection of axes, or nearly so, in order that the plate member 224 shall have a minimum of rocking movement.

The scheme of the valve structures comprising the control means 210, is in simpler fashion shown in Fig. 15, then is readily discernible from its actual construction set forth in Figs. 17 and 18. Hence reference is had to the showing of said means 210 in Fig. 15. The numerals 235 and 236 denote check valves. The check valve 235 permits passage of sealing compound from pipe 209, through itself, and then into and out of pipe 211, back to the hopper 206. The check valve 236 permits passage of sealing compound from the pipe 209, through itself, and then into and out of the pipe 211, back to the hopper 206. However, there is a valve means interposed between said check valve 236 and the pipe 209; such valve means, including the slide rod 223 whose movement controls the passage of sealing compound from the pipe 209 to the check valve 236. It is evident that such check valves prevent the flow of sealing compound from the hopper 206 through pipes 215 and 211, then through the pipe 209. The pipe 209 may therefore be deemed the intake passage to the control means 210, and pipe 211 as the discharge passage thereof. Said control means is in what may be deemed the return passage to the hopper 206, for that portion of the sealing compound fed to the shaft 63, which is more than the nozzle needs to do its work properly.

Being that the pumps 205 and 208 operate to produce an excess of supply of sealing compound in the packing box 88, in order to insure the presence of sufficient quantity under sufficient pressure for proper working at sealing operation, the check valve 235 which has nothing interrupting its action, permits the excess material from the packing box 88, to return to the hopper. The excess mentioned is of course increased when the nozzle 79 is not discharging. Therefore to maintain an even discharge pressure at nozzle orifice and avoid initial massive squirts of material from the nozzle, the valve controlled by operation of slide rod 223, is "opened" while the nozzle is not discharging or out of discharging position during the cycle of operation of the machine, so that such great excess of sealing substance may have another passage to the hopper 206, through the line controlled by the check valve 236. All this allows a relief of excess pressure and excess material to "build up" when no sealing compound is being extruded from the nozzle while it is not in sealing position, so that when the machine does operate, there is assured an even seal around the bottle or container.

The block member 221 is therefore formed with ducts in the relationship to effect the passageways controlled by the valves shown included therein in Fig. 15. So in Figs. 17 and 18, and in correspondence with numerals in Fig. 15, the numeral 231 is one passageway and 238 another. The check valves 235 and 236 may be of the adjustable spring-loaded ball

50

type of valve shown in Fig. 17; both such valves being of identical structure, what is said as to the structure of one, is the same for the other. The numeral 239 is a ball acted on by a compression coil spring 240, whose pressure against the ball is adjustable by means of the accessible screws 241 and 242 respectively.

It is evident that the greater the pressure exerted on the valve balls 239, the greater the amount of sealing compound will be that is forced from the main shaft packing box 88, through such shaft to the nozzle. Of course, the discharge pressure will also be considerable. Changes in supply quantity and pressure is effected by manipulation of the adjustment screws 241 and 242. Release of spring pressure on the valve balls 239, permits a greater amount of sealing compound to return to the hopper 206, and hence discharge pressure through the nozzle is reduced.

In order that the block 221 may be provided with holes as shown to have the required passageways in proper communicative relation, the open forward ends of the bores 231' and 237'' need be closed by suitable plugs designated by the numerals 243 and 244 respectively.

The construction of the cam means which serve to raise and lower the nozzle 79, will now be described; reference being had to the parts 119, 120 and 121 which are formed of the original one-piece structure designated generally by the numeral 245 shown in Figs. 25-27, of which the Fig. 28 is a development view.

This structure 245 is essentially a cylindrical tubular body. Nearly two-thirds around its periphery, it is of one radius as outside dimension. The remainder around its periphery is of a lesser outside radius. Intermediate the ends of the structure 245, the body portion of greater outside radius has a channel 246 therealong. Intermediate the ends of said structure 245, the body portion of outside lesser radius has a flange 247. The outside radius of the flange 247 is equal to the outside radius of the body portion having the channel 246. The outside radius of the body portion having the flange, is equal to the radius measured to the floor surface of the channel. Hence, if a follower as 118 of Fig. 22, were positioned to ride along the channel 246, said follower would emerge from either end of said channel onto the body portion having the flange.

Consider the structure 245 as set upright on one of its ends as in Fig. 25, because the three parts 119, 120 and 121 made therefrom, of which the latter two are movable, are all positioned on the machine in the relationship they are in said Fig. 25.

Referring now to Fig. 28, both ends of channel 246 start horizontal in alignment and continue so 60 a comparatively short distance as shown at A and a respectively, and then each rises gradually as along B and b respectively, to a comparatively long horizontal central part C. The flange 247 is horizontal with its lower face 247' in position to be contacted by the upper side of the follower 118, if said follower would leave either end of said channel 246. The thickness of said flange 247 is such that its upper face 247'' is in position to be contacted by the underside of the follower 118 if said follower is raised to the level it would be while in the channel region C, and swung around at such level to the flange 247.

The structure 245 is cut along the lines DE, FG and EG; the latter being along the center line of the channel 246, to yield the cam part 120.

Said structure 245 is cut along the lines HK, LM and KM; the latter being along the center line of the channel 246, to yield the cam part 121. Parts 120 and 121 are symmetrical. What remains of the structure 245 is designated as the cam part 119. This part 119 is suspended fixed from the underside of the main plate 56. The upper portions S and T respectively are cut away from the cam parts 120 and 121.

Referring to Fig. 29, the follower means 122 comprises a bracket-piece 248 for the roller 249. Downwardly from said bracket-piece extend a pair of spaced vertical rods 250 which carry the cam part 120 at their lower ends. These rods are slidably mounted through the main plate 56, and have the compression springs 251 about them as shown, to maintain the roller 249 in contact against the cam track 129 on the underside of the cam gear 66.

Referring to Fig. 30, the follower means 123 includes a bridge-piece 252, downwardly from which extend a pair of spaced vertical rods 253 carrying the cam part 121 at their lower ends. These rods are slidably mounted through the main plate 56. It would seem that bridge-piece 252 could be like the bracket-piece 248 with a roller similar to 249 for contact with the cam track 126 on the underside of the cam gear 66. Such would be preferred and is possible, but various mechanical conditions are brought about which make it least practical, because the cam tracks for raising the cam parts 120 and 121, meaning the cam tracks 129 and 126, would have to be adjacent each other, but such construction is impractical in the embodiment illustrated due to the presence of other mechanism already included which is differently positioned would present both structural and operational difficulties and make the size of the cam gear 66 unduly large. I therefore use the contrivance shown in Fig. 30 as the cam follower means associated with the cam part 121, for movement of the latter.

This contrivance 123 utilizes a lever 254 pivoted at 255 at one end atop a stud 256 extending upwardly from the main plate 56. The other end of said lever carries a pair of demountable jaw-like members 257 which grip the bridge-piece 252 between them; providing a pivotal connection of said lever and bridge piece which is facilitated because said flat bridge-piece is contacted between the cylindrical forms 257' along the jaw edges. A roller 258 is atop a post 259 whose shank 259' is vertically slidably mounted through the main plate 56. This post 259 is positioned through the body of the lever 254, which is pivotally connected thereto by a pin 260 through an enlarged hole 261 in the body of the post. Tension springs 262 connecting said lever and a U-piece 263 as shown, serve to hold the roller 258 in contact with the cam track 126 on the underside of the cam gear 66. It is advisable that the post 259 carry an auxiliary roller 145 which is adapted to be met by the upward sloping surface 144' of a cam piece 144 fixed depending from the underside of the cam gear 66. This is to insure that at a certain predetermined time, the cam part 121 shall be in raised position out of the way of the follower 118. So, if springs 262 for any reason fail to act, the raising of the cam part 121 is assured.

It might here be noted that the cam means comprising the parts 119, 120 and 121, are arranged concentrically about the axis of the main shaft, and particularly positioned about the fixed

tubular member 59, directly above and free of the nozzle gear 64. The lever 254 extends radially of the main shaft axis and towards the front of the machine, with its jaws 257 nearest to such axis. It may also here be noted that when a bottle 82 or other container engaged by the "star" wheel 266, is at rest position in axial alignment with the axis of the main shaft 63, such bottle or the like is in "sealing" position.

When a bottle has just arrived in sealing position, the relative positions of the cam parts 119, 120 and 121, are shown in Fig. 32, where cam part 121 is in lowered position and cam part 120 is in its raised position. Follower-roller 118 has just entered region *a* of the track or channel offered by the cam parts 119 and 121.

It may here be noted that the direction of rotation of the cam gear 66 and of the nozzle gear 64, is clockwise, with nozzle gear making two revolutions for each revolution of the cam gear. When roller 118 is at regions *A* or *a* in contact with cam part 119, the nozzle 79 is in its raised position away from sealing position. When the roller 118 is at region *C* in contact with cam part 119, the nozzle is in its lowered position at sealing position. When the roller 118 is riding on top of the flange face 247", said roller is maintained at a level as it would be along region *C*. When the roller 118 is riding in contact with the flange's underside 247', the roller is maintained at a level as it would be along regions *a* and *A*. The lowered position of cam parts 120 and 121, is where they offer a track with cam part 119 for the said roller 118. The raised position of the cam parts 120 and 121, is where they are high enough to clear the passage of the roller 118 raised to the lever offered at region *C*. Upon rise of the roller 118 from region *a* to region *C*, the nozzle 79 is lowered from upward rest position to lowered discharge position. Descent of said roller 118 along the vertical, brings the nozzle 79 upward.

To explain the movement of the roller 118 along the vertical during two consecutive revolutions of the nozzle gear 64, reference will be had to the Figs. 32 and 33. At commencement of the first revolution which is just as a bottle has arrived in sealing position, cam part 121 is in lowered position, the cam part 120 is in raised position, and the roller 118 has just entered region *a* of the track offered by the cam parts 119 and 121. From here, the roller 118 rides up channel region *b* to the high level of region *C*. The nozzle 79 is now in sealing position. The roller 118 continues at the high level as it passes free under cam part 120 and thence onto the upper face 247" of the flange. Now cam part 121 is in raised position and cam part 120 is in lowered position as in Fig. 33, before the nozzle gear 64 has completed one revolution. The roller 118 emerges from off the flange 247, passes under the cam part 121, remains at the level as region *C*, passes then along region *C* of cam part 119, and into the channel or cam track offered by cam parts 120 and 119, down region *B* and into region *A* and thence said roller 118 rides below the flange 247 in contact with the underside thereof and continues to complete the second revolution of the nozzle gear when all parts are again in condition as shown in Fig. 32.

It is to be noted that the roller 118 was at high level and hence the discharge nozzle 79 was at sealing position, for more than one revolution of the nozzle gear 64. It is therefore arranged that discharge of sealing compound shall occur

during a little more than one revolution of the nozzle gear while the nozzle 79 is down in sealing position. This accomplishes an overlap in the band of sealing compound performed around the neck of the bottle.

That cam part 121 will be in raised position as in Fig. 33 when the roller 118 is to pass under it at high level, is assured by action of the auxiliary cam parts 144 and 144' which cooperate before the end of the first revolution of the nozzle gear 64. Also to be noted is that provision is made to maintain the ultimate raised and lowered positions of the roller 118, and hence likewise of the nozzle 79, by an indexing means comprising a disc 191 which is next to and rotates with the gear 113, shown in Fig. 22. The numeral 278 indicates a spring-loaded latch slidably mounted in the socket member 271 of the bracket 115, from which socket said latch extends towards the periphery of the disc 191, where it terminates in a roller adapted for engagement in either of the disc's peripheral notches 276 and 275; said roller 274 being releasable from said notches upon rotation of the gear; said notches being at such places on the disc as determine low and high positions for the roller 118. The notch 275 is engaged by the latch when the roller 118 is at the level of the region a. The notch 276 is engaged by the latch when said roller is at the level of the region C in Fig. 28.

All cam tracks on the cam gear 66, are circular rings extending from the respective faces of such gear, in concentric relation with said gear. All such cam tracks are designed to properly move their respective followers in such fashion as to accomplish the following operations in the sequence and in timed relation required of them, as will now be set forth. Since a complete cycle of operation of the machine occurs for each revolution of the cam gear, and the function and operation of the individual parts having been explained, it will be convenient to explain the operation of the machine as a whole by setting forth the occurrence of activity as the cam gear 66 turns 360 degrees, meaning one revolution. As "zero" degree position of the cam gear, that position will be assumed where the centering cup 77 is in remote downward position engaging the bottle cap 81, thereby adjusting the bottle 82 to set in true "sealing" position. Of course, the bottle having moved to sealing position, has contacted the arm 163 and has moved same so that block member 164 is shifted away as shown in Fig. 14, whereby the follower roller 146 is free to be lowered in due time to cause the opening of the nozzle valve 93.

The occurrence of activity as the cam gear 66 turns 360 degrees, is as follows:

At 0 degrees, the centering cup 77 is down, as mentioned.

At 1½ degrees, the hold-down rod 78 is in its remote downward position, pressing on the bottle cap 81 to maintain the bottle 82 in true sealing position. Also the centering cup 77 starts to move upwards.

At 2½ degrees, the roller 138 contacts the cam face 139' to assure that the centering cup 77 is lifted.

At 10 degrees, the roller 146 is in its lowered position, ready to act on cam 141 for the opening of the nozzle valve 93.

At 12½ degrees, the centering cup 77 has reached its raised position, and the nozzle 79 has come down to sealing position.

At 13 degrees, the nozzle valve 93 starts to open.

At 17½ degrees, said nozzle valve is fully open.

At 32 degrees, the cam part 121 starts upwardly.

At 33 degrees, the cam part 120 is fully raised.

At 78 degrees, roller 146 starts to be raised.

At 96 degrees, the roller 146 is fully raised.

At 105 degrees, the cam part 120 starts downwardly.

At 140 degrees, the cam part 121 is fully raised.

At 181 degrees, the roller 149 starts to descend.

At 200 degrees, said roller 149 is in its lowered position, ready to act on cam 143 for the closing of the nozzle valve 93.

At 201¾ degrees, the nozzle valve 93 starts to close.

At 206½ degrees, the nozzle valve 93 is closed.

Of course, while the nozzle valve was opened,

sealing compound was discharged from the nozzle 79 onto and around bottle neck and cap 81, more than once around. Hence there is an overlap in the band accomplished to effect a secure seal.

At 212 degrees, the cam part 121 which was in raised position, starts to move downwardly.

At 213 degrees, the cam part 120 has fully descended.

At 215½ degrees, the nozzle 79 starts to swing upward.

At 217 degrees, the hold-down rod 78 starts to ascend.

At 218½ degrees, the star-wheel 266 starts to turn and shift the bottle just sealed, away from sealing position, and to bring another bottle toward sealing position.

At 224 degrees, the roller 149 starts to ascend.

At 225½ degrees, the hold-down rod 78 is fully raised.

At 242 degrees, the roller 149 is fully raised.

At 265½ degrees, the nozzle 79 has reached its remote upward position, as shown at 79' in Fig. 9.

At 285 degrees, the cam part 120 starts to ascend.

At 320 degrees, the cam part 121 is fully descended as in Fig. 32.

At 322 degrees, the nozzle 79 starts to move downward.

At 345 degrees, the centering cup 77 starts to descend.

At 346 degrees, the hold-down rod 78 starts to descend.

At 350 degrees, the roller 146 starts to descend.

At 352½ degrees, the star-wheel 266 stops, and the next bottle to that just sealed, is at sealing position, ready to receive the centering cup 77.

At 360 degrees, the centering cup is fully descended into position as at zero degrees. The machine has performed a complete cycle of operation.

The conveyor system shown in part in Figs. 1 and 2, need not be gone into in great detail because it is well known in the machine art to have a bottle-carrying endless conveyor belt 270 bring one bottle at a time into the "star wheel" 266,

and then to have another endless conveyor belt 271, carry a bottle which has been worked on by the machine, away to a suitable delivery point; the said conveyor belts being in constant movement while the star wheel 266 is associated with

suitable mechanism not shown, for accomplishing periodic motion for shifting the star wheel a predetermined part of a revolution in proper timed relation, once during each revolution of the cam gear 66. The conveyor belts 270, 271, and the mechanism for operating the star wheel 266, may

be driven from the power shaft 71, or in other suitable manner.

Because the heights of bottles presumably of the same size do vary somewhat, and since it is desired that the band seal performed by the machine shall be uniform for all bottles with respect to rim edge of the cap 81, and to assure a full descent of the hold-down rod 78, the spring-loaded platform 272 is provided at sealing position of the machine; the normal position of said bottle-platform 272 being in the plane of the stationary platform 269.

To set the machine for operation, the motor driving the power shaft 71 is operated in "edging" manner until the machine is at rest with its nozzle 79 in most lowered position. At this time, the centering cup 77 is in raised position, and the hold-down rod 78 is in its lowered position. A capped bottle 82 of the kind to be used for the run, is set on platform 272. The position of the nozzle 79 is then adjusted so that its discharge orifice is a proper distance from the top and neck of the capped bottle 82, as experience will dictate. This is done by manipulation of the handwheel 53 and by adjustment of the spool nut 201, so that the hold-down rod 78 pushes on the bottle cap 81 whereby the platform 272 is a little below the plane of the platform 269, and by the setting of the bolts which mount the nozzle, after adjustment of the nozzle halves 198 and 199, to desired position.

The bar 163 is adjusted on rod shaft 161 to contact the back of bottle in Fig. 1, so that block 164 is clear of the flange 161'. The hopper 206 is then filled with sealing compound, capped bottles to be sealed are fed to the conveyor belt 270, and the machine is let run. Proper nozzle flow is then effected by adjustment of the screws 241 and 242 of the check valves built in block 221 shown in Fig. 17, and the hand valve 214; the function of the latter being to assure a pressure at entrance port to the pump 208, by limiting return of sealing compound to the hopper 206. For adjustment of the lowered positions of the hold-down rod 78 and the centering cup 77, they carry the spool-nuts 201 and 202 respectively on their upper threaded end portions. These nuts are engaged by the swing arms 134 and 135 as shown in Fig. 1, and upon axial rotation, they respectively change the position of the hold-down rod and the centering cup, along the vertical.

It is to be noted that because the nozzle 79 is made to move away from the bottle just sealed, and due also to the movement of said nozzle along with the nozzle gear 64, there is a clean breaking off of the "ribbon" without drippings onto the bottle, of any sealing compound remaining at nozzle mouth.

It is evident that the operation of the machine is continuous, fully automatic, with provision that there will occur no discharge through the nozzle 79, if a bottle or other container is not at sealing position.

Suitably opening hoods, casings and guards may be mounted about the machine or parts of its mechanism as is good engineering and safety practice.

Other contributions which I have made to this art are set forth in Patents Nos. 2,019,841, 2,081,908 and 2,103,213.

The present invention is capable of various forms and applications without departing from the essential features herein disclosed. It is therefore intended and desired that the embodiment herein be deemed illustrative and not re-

strictive and that the patent shall cover all patentable novelty herein set forth; reference being had to the following claims rather than to the specific description herein to indicate the scope of this invention.

I claim:

1. In a container sealing machine having a frame, a container supporting means on the frame, means for discharging sealing fluid onto the joint between a container and its closure on said supporting means, a member rotatably mounted on the frame for movement about a line surrounded by such joint, means for constantly rotating said member in one way about said line; said discharge means being swingably mounted on said member and movable thereon towards sealing position and away from sealing position; the axes of such rotation and swing being in angular relation and means to shift the discharge means with respect to said member whereby said discharge means will remain at sealing position for more than one and less than all of every occurrence of a predetermined number of complete circuitous movements of said member about said line.

2. A machine as defined in claim 1, wherein the axis about which said member carrying the discharge means is rotatably mounted on the frame, is vertical and the axis about which the discharge means is swingably mounted on said member, is horizontal.

3. A machine as defined in claim 1, wherein the axis about which the member carrying the discharge means is rotatably mounted on the frame, is vertical and the axis about which the discharge means is swingably mounted on said member, is horizontal, whereby the direction of swing towards sealing position is downward; said discharge means at sealing position being at least in part between the planes determining the top and bottom of the container and said discharge means when moved upwardly away from sealing position, being above the plane of the top of the closed container.

4. In a container sealing machine having a frame, a container supporter means on the frame, means for discharging sealing fluid onto the joint between a container and its closure on said supporting means, a member carried on the frame, capable of movement about a line surrounded by such joint, means for constantly moving said member in one way about said line; said discharge means being carried by said member and movable thereon towards sealing position and away from sealing position, means to shift the discharge means with respect to the said member whereby said discharge means will remain at sealing position for more than one and less than all of every occurrence of a predetermined number of complete circuitous movements of said member about said line, valve means controlling the flow of sealing fluid to the discharge means, means operating said valve means whereby there is a flow of sealing fluid from the discharge means substantially only when the discharge means is at sealing position and at least during one and a fraction revolutions of the member carrying the discharge means, a shiftable member normally holding the valve operating means in inactive condition, a means operated by the movement of a container towards the container supporting means whereupon said holding member is shifted to release the valve operating means for operation and means to restore said holding member

to normal position after the valve has been operated.

5. A machine as defined in claim 4, wherein the valve operating means includes a member slidably mounted on the frame; said slidable member being at a predetermined rest position while the discharge means is away from sealing position and being capable of being moved to another position to effect setting the valve means in open condition, and wherein the mentioned holding means comprises a member acted on by a spring to maintain such holding member in such a position that the said slidable member is held against movement from said predetermined rest position and a shaft rotatably mounted on the frame, carrying said holding member and also having an arm extending into the path of a container being moved towards the container supporting means, whereby said arm on being contacted by such moving container, said arm is shifted to turn the shaft whereupon the holding member is shifted to free the slidable member of the valve operating means for movement and a spring means to restore said slidable member to normal rest position after said member has moved from such position.

6. A machine as defined in claim 5, including another member slidably mounted with respect to the frame, for movement along a line parallel to the line of movement of the slidable member which cooperates with the holding member and serving as a follower contacting a cam revolvably mounted on the frame and a relatively stiff spring means acting to separate said slidable members and capable of yielding to permit movement of the slidable member associated with said cam when the other slidable member is held against movement by the holding member and further being unyielding when the holding member is shifted to release its associated slidable member for movement, whereupon movement of the said cam to shift the slidable member acting as its follower towards the other slidable member, the latter is slid to its position away from the predetermined rest position for actuation of the valve operating means; the spring acting to restore such latter slidable member, being relatively weak.

7. In a container sealing machine having a frame, a container supporting means on the frame, means for discharging sealing fluid onto the joint between a container and its closure on said supporting means, a member carried on the frame, capable of movement about a line surrounded by such joint, means for constantly moving said member in one way about said line; said discharge means being carried by said member and movable thereon towards sealing position and away from sealing position, means to shift the discharge means with respect to said member whereby said discharge means will remain at sealing position for more than one and less than all of every occurrence of a predetermined number of complete circuitous movements of said member about said line, valve means controlling the flow of sealing fluid to the discharge means; said valve means being carried along with the discharge means and having a slidably mounted member with exposed ends; the position of said slidable member determining the opening and closing of said valve means and means for shifting said slidable member whereby there is a flow of sealing fluid from the discharge means substantially only when the discharge means is at sealing position comprising a pair of

shafts mounted for axial rotary movement on the constantly movable member, a pair of arms extending laterally, one from each of said shafts respectively adjacent the ends of said slidable valve member when the discharge means is at sealing position and adapted upon axial rotary movement of said shafts to respectively contact the respective ends of the said slidable valve member and shift same; the movement of one of said arms away from a normal rest position accomplishing shifting of the slidable valve member so that the valve is in open condition and movement of the other of said arms from a normal rest position accomplishing reverse shifting of the slidable valve member so that the valve is in closed condition, separate cam means on each of said shafts and separate means cooperating with said cam means respectively whereby said shafts are axially rotated part of a revolution in proper timed relation with the movement of the discharge means with respect to sealing position, to shift the slidable valve member so that the valve is set in open condition when the discharge means is in sealing position and to be in closed condition when the discharge means is away from sealing position and a means to restore said shafts to their respective normal rest positions where the arms thereon are respectively adjacent the positions assumed by the respective ends of the slidable valve member which are most distant from each other.

8. A machine as defined in claim 7, wherein the member carrying the discharge means is rotatably mounted on the frame about a vertical axis, the discharge means is swingably mounted on said member about an horizontal axis, the shafts carrying the valve-operating arms are vertical, the slidable valve member is mounted for movement along the horizontal and the movement of the discharge means towards sealing position is downward.

9. In a container sealing machine having a frame, a container supporting means on the frame, means for discharging sealing fluid onto the joint between a container and its closure on said supporting means, a shaft rotatably mounted on the frame; the axis of rotation of said shaft being surrounded by such joint; said discharge means being carried along with the shaft and movable with respect thereto towards said axis to sealing position and away therefrom, a cam-carrying member rotatably mounted with respect to the frame, means to rotate said shaft and cam-carrying member whereby the shaft will make two revolutions for each revolution made by the cam-carrying member, a substantially cylindrically shaped cam structure positioned substantially in alignment with said shaft, comprising a main cylinder-like cam portion fixed to the frame and a pair of cam portions independently movably mounted on the frame for movement towards and away from the said main cam portion, a follower carried along with the shaft, cooperating with said cam structure and in connection with the said discharge means, whereby the discharge means is moved to and from sealing position; the main portion of the said cam structure having a lateral flange extending partially around its circumferential surface and so dimensioned that when the cam follower is in contact with one face of said flange, the discharge means will be at sealing position and when in contact with the other face of said flange, the discharge means will be away from sealing position; said main portion of the

cam structure, in cooperation with the movable cam portions of said cam structure, offering around the entire remainder of the circumferential surface of said cam structure between the ends of said flange when both said movable cam portions are in their positions nearest the said main cam portion, a track for guiding said follower, whereby on movement of said follower along such track, said follower will be shifted from the position it need be for contact with one of said flange surfaces to a position it need be for contact with the second flange surface while said follower is in contact with the main cam portion and one of the movable cam portions and then back again to the position it need be for contact with the first of said flange surfaces while said cam follower is in contact with the main cam portion and the other of said movable cam portions, a first cam means on the cam-carrying member adapted upon rotation of said member, to shift one of the movable cam portions of the cam structure towards and away from said main cam portion, a second cam means on the cam carrying member, adapted upon rotation of said member, to shift the other movable cam portion of the cam structure towards and away from the said main cam portion; the design of the cam means on the cam-carrying member being such that when any one of the movable cam portions of the cam structure is in position nearest to the said main cam portion, the other movable cam portion of said cam structure is substantially in position furthest from said main cam portion and whereby alternately within one revolution of the shaft, the follower is in contact with one surface of the said flange on the main cam portion of said cam structure and within the next revolution of the shaft, said follower is in contact with the other surface of said flange; said movable cam portions of the cam structure when in their respective positions nearest the main cam portion of said cam structure, extending respectively from the ends of said flange and circumferentially of the main portion of said cam structure.

10. A machine as defined in claim 9, wherein the cam structure mentioned is so designed that the cam follower is in position holding the discharge means at sealing position for more than one out of every two revolutions of the shaft.

11. A machine as defined in claim 9, including engagement means carried on the shaft, adapted to automatically engage the discharge means and releasably hold same in its remotest positions respectively.

12. A machine as defined in claim 9, wherein the cam-carrying member is a gear positioned and free to revolve on the shaft and wherein said shaft has a gear fixed thereon; the discharge means and follower being respectively movably mounted on said latter gear.

13. A machine as defined in claim 9, wherein the shaft is provided with an axial bore therethrough and including a tubular member slidably extending through said bore in the shaft, adapted on movement in one direction, to receive into one end thereof part of a container on the container supporting means and to shift such container to a predetermined position on said supporting means, a hold-down rod slidably extending through said tubular member, adapted when slid in said same direction, to pressingly engage only the closure and thereby hold such container in said predetermined position and cam means on the cam-carrying member, adapted

upon rotation of said cam-carrying member, to shift said tubular and rod members respectively in said direction and in reverse direction in proper timed relation with the movement of the discharge means in relation to sealing position, whereby the discharge means and said tubular member remain out of contact; the movement of the tubular member precedes movement of the rod in like direction and said rod leaves the closure after the discharge means commences movement away from sealing position.

14. In a container sealing machine having a frame, a container supporting means on the frame, means for discharging sealing fluid onto the joint between a container and its closure on said supporting means, an upright shaft rotatably mounted on the frame; said shaft having an axial bore therethrough; the line of the axis of said shaft being surrounded by such joint; said shaft having its upper portion of reduced diameter, an annular channel in the top of the shaft portion of larger diameter, surrounding the lower part of said reduced portion and a non-axial longitudinal passage for sealing fluid opening at the bottom region of said shaft and extending upwardly to substantially the region of said annular channel; said passage and annular channel being communicative, means making the bottom opening of said passage communicative with said discharge means; said discharge means being carried along with said shaft below such passage opening in said shaft; a removable sleeve threadedly engaging said shaft positioned about the reduced portion of said shaft and extending into said annular channel; said sleeve having a flange in leak-proof contact with the top end of the shaft portion of larger diameter and said sleeve being in leak-proof contact with the upper part of the reduced shaft portion and in spaced relation with the remainder of said reduced shaft portion whereby another annular channel is formed between the lower part of the sleeve and the lower part of said reduced portion of the shaft; said annular channels being communicative, a bearing-like means detachably mounted on the frame, separable from said sleeve and serving as an encasement for said sleeve; said bearing means having an intake port for receiving sealing fluid from a supply line; said sleeve being provided with at least one opening through its wall into the said second mentioned annular channel, adapted to register with said inlet port upon rotation of the shaft.

15. A machine as defined in claim 14, wherein the bearing means is also provided with an outlet port for sealing fluid; the opening in the sleeve being also adapted to register with said outlet port; said outlet port being connected to the supply line.

16. A machine as defined in claim 14, wherein the bearing means in a packing box comprising separable longitudinal parts and having at least three internal annular races, one over the other; an intermediate race having the intake port and packing material filling each of the other races.

17. A machine as defined in claim 14, wherein the bearing means is a packing box comprising separable longitudinal parts and having at least three internal annular races, one over the other; an intermediate race having the intake port and also an outlet port for sealing fluid; the opening in the sleeve being communicative with said intermediate race and said outlet port being connected to the supply line.

18. A machine as defined in claim 17, wherein

the packing box depends from a frame part having a hole whose bottom is closed by said box and wherein the sleeve extends through the packing box and into said hole; the said hole so closed being adapted to hold a liquid lubricant adapted to seep to the packing.

19. A machine as defined in claim 17, including a receptacle having a hole through its bottom and carried by the packing box whereby said box extends into and upwardly from said receptacle; the sleeve being positioned through said hole in liquid-proof contact with the receptacle bottom; said receptacle being adapted to hold a liquid lubricant adapted to seep to the packing.

20. In a container sealing machine having a frame, a container supporting means on the frame, means for discharging sealing fluid onto the joint between a container and its closure on said supporting means; said discharge means being movably mounted on the frame, capable of movement to and from sealing position, means for moving said discharge means to and away from sealing position, container centering means movably mounted with respect to the frame, cam means for moving said centering means towards the container on the supporting means, spring means to restore said centering means to its position away from container and auxiliary cam means adapted to restore said centering means to its position away from the container on the supporting means in the event said spring means fails to do so; the path of movement of the discharge means being in intersecting relation with the path of movement of the centering means; said spring means and auxiliary cam means being adapted in restoring said centering means to its position away from the container, to act in time so that said centering means is out of the path of the discharge means.

21. In a container sealing machine having a frame, a container supporting means on the frame, means for discharging sealing fluid onto the joint between a container and its closure on said supporting means; said discharge means being movably mounted on the frame, capable of movement to and from sealing position, a cam follower adapted on movement to shift the discharge means, cam means cooperating with said follower for moving said discharge means from

5 a position away from sealing position to sealing position whereupon a part of said cam means is in the path of said follower, a spring to cause said part of the cam means to move out of the path of said follower when the discharge means is at sealing position and auxiliary cam means adapted to act as required of said spring in the event said spring fails.

10 22. In a container sealing machine having a frame, a container supporter means on the frame, means for discharging sealing fluid onto the joint between a container and its closure on said supporting means, a member carried on the frame, capable of movement about a line surrounded by such joint, means for constantly moving said member in one way about said line; said discharge means being swingably mounted on said member and movable thereon towards sealing position and away from sealing position; the said line and the said axis of swing being in angular relation, and means to shift the discharge means with respect to the said member whereby said discharge means will remain at sealing position for more than one and less than all of every occurrence of a predetermined number of complete circuitous movements of said member about said line.

15 23. A machine as defined in claim 22, wherein said discharge means when at sealing position, is at least in part between the planes determining the top and bottom of the closed container, and said discharge means when moved away from the mentioned line, is in a position which is outside the space determined by said planes.

20 HENRY B. SILVER.
